UNITED STATES PATENT OFFICE

126,458

DESIGN FOR A COAT

Edna Breer, New York, N. Y.

Application January 4, 1941, Serial No. 97,821

Term of patent 3½ years

To all whom it may concern:

Be it known that I, Edna Breer, a citizen of the United States and a resident of the city of New York, in the county of New York and State of New York, have invented a new, original, and ornamental Design for a Coat, of which the following is a specification, reference being had to the accompanying drawing, forming a part thereof.

Fig. 1 is a front view of a coat showing my new design.

Fig. 2 is a rear view of the coat as shown in Fig. 1.

I claim:

The ornamental design for a coat, substantially as shown.

EDNA BREER.
